UNITED STATES PATENT OFFICE.

TOM M. ANDERSON, OF MAYER, ARIZONA.

REFRIGERATOR.

1,232,474.

Specification of Letters Patent. Patented July 10, 1917.

Application filed April 22, 1916. Serial No. 92,923.

To all whom it may concern:

Be it known that I, TOM M. ANDERSON, a citizen of the United States, residing at Mayer, in the county of Yavapai and State 5 of Arizona, have invented certain new and useful Improvements in Refrigerators, of which the following is a specification.

This invention has relation to refrigerators, and the nature and objects thereof will 10 be readily apparent to those skilled in the art to which it appertains, in the light of the following explanation of the accompanying drawings, illustrating what I now believe to be the preferred embodiment, or 15 mechanical expression, of my invention from among other forms and arrangements within the spirit thereof, and the scope of the appended claims.

However, an object of the invention is to 20 provide a refrigerator for containing foods to be preserved and in which the refrigerating medium consists of water and air circulated throughout the refrigerator, in a novel manner, whereby the temperature therein is 25 lowered by evaporation of the water in accordance with a well known principle.

Another object of the invention is to provide evaporating surfaces of large extent in a refrigerator of the character described, 30 whereby the lowest possible degree of temperature may be obtainable.

In addition to the foregoing my invention comprehends improvements in the details of construction and arrangement of parts to 35 be hereinafter described and particularly pointed out in the appended claim.

In the accompanying drawings in which similar and corresponding parts are designated by the same characters of reference 40 throughout the several views in which they appear;

Figure 1, is a view in side elevation, partly in section, of a refrigerator constructed after the manner of my invention.

Fig. 2, is a central vertical section through the refrigerator.

Fig. 3, is a horizontal section on the line 3—3 of Fig. 1, and

Fig. 4, is a horizontal section on the line 50 4—4 of Fig. 1.

With reference to the drawings my refrigerator comprises in its essentials a substantially cylindrical body portion 1 having a central vertical chamber 2 in which food to be preserved may be stored upon shelves or the like (not shown), access to

said chamber being had through the provision of a lateral opening 3 at the lower portion thereof, normally closed by an airtight door 4.

The walls of the container thus formed are relatively thick so as to permit the provision therein of a pair of helical channels 5 and 6, concentrically disposed around the central chamber, and having their lower ends connected by the passage 7. The helical channels 5 and 6 extend in their convolutions throughout the length of the refrigerator, and one of the channel formations is relatively greater in diameter than 70 the other so as to define partitions 8 between adjacent convolutions.

One of the channels is in connection at the upper portion of the refrigerator with an air inlet 9 connected to the channel 6, and 75 the other with an outlet 10 connected to the channel 5. Water inlet pipes 11 are also connected to the channels at their upper portions.

In operation water is injected into the 80 channels through the pipes 11, circulates through the convolutions of both channels and descends by gravity to the lower ends of the channels and into the outlet 12 in the passage-way 7 to a waste conduit. At the 85 same time air under low pressure is forced into the upper portion of the channel 6, through the inlet 9 and thence throughout the convolutions of said channel to the lower end thereof, through the passage-way 7 and thence upward again into the convolutions of the channel 5. The water is not permitted to entirely fill the channels but form a space through which the air may be caused to circulate, in this manner causing the 95 evaporation of the water and lowering the temperature of the refrigerator walls. The efficiency of this form of refrigerator may be greatly increased by forming the same of porous material, and especially the walls 100 of the partitions 8, the water permeating through the pores of the partition thereby exposing a greater surface for evaporation and affording a greater reduction of temperature. During the circulation of water 105 and air through the channels, the air within the chamber 2 becomes cooled and if desired a cover may be placed over said chamber to prevent the entrance of heated air.

While I have illustrated and described 110 my invention with some degree of particularity, various ways of reconstructing the

same to employ the principle involved will occur to those skilled in the mechanical arts, I therefore reserve the right and privilege of changing the form of the details of construction, or otherwise altering the arrangement of parts, without departing from the spirit of the invention or the scope of the appended claim.

Having thus described my invention, what 10 I claim as new and desire to secure by Letters Patent is:—

A refrigerator including a body portion

having a central opening and relatively thick walls, said walls being provided with a pair of helical channels encircling the chamber 15 and connected at their lower ends, and having an outlet at said lower ends, and water and air inlets at their upper ends.

In testimony whereof I affix my signature in presence of two witnesses.

TOM M. ANDERSON.
